HER ATTORNEY

UNITED STATES PATENT OFFICE

SARAH E. BOHNER, OF SAN FRANCISCO, CALIFORNIA

EYELID GUARD

Application filed October 20, 1931. Serial No. 569,974.

My invention relates to an implement for use in connection with the application of cosmetics, and particularly to a guard for protecting the eyelid when the eyelashes are being colored or painted.

It is among the objects of my invention to provide a guard by the use of which coloring matter may be painted or otherwise applied to the eyelashes without danger of the paint becoming smeared over the eyelid.

Another object of my invention is to provide a guard which will assist in the application of the coloring matter by supporting the eyelashes during the painting operation.

15 Further objects of my invention include the provision of an eyelid guard of the character described which may be used conveniently and without discomfort.

The invention possesses other objects and 20 features of advantage, some of which, with the foregoing, will be set forth in the following description of my invention. It is to be understood that I do not limit myself to this disclosure of species of my invention, as I 25 may adopt variant embodiments thereof within the scope of the claims.

Referring to the drawing:

Figure 1 is a side elevational view showing 30 the eyelid guard embodying my invention; and

Figure 2 is an end view of the same.

Figure 3 is a perspective view showing the guard in use.

In terms of broad inclusion, the eyelid 35 guard embodying my invention comprises a preferably flexible sheet curved to fit over the eyeball and having an edge thereof curved to register with the edge of the eyelid when closed; the guard being adapted for placement between the eyelid and eyelashes to support the lashes and to protect the lid when the lashes are being painted or otherwise colored. In the preferred form of my invention the guard sheet is of a light material, such as celluloid, and has preferably integrally formed therewith a handle for assisting in manipulating the guard.

In greater detail, the eyelid guard embodying my invention comprises a sheet 2 preferably of a light flexible material, such as cellul-

loid, and has preferably integrally formed therewith a suitable handle 3. The handle 3 may be formed in any desirable manner, such as by coiling up an elongated portion of the sheet into a cylindrically shaped handle, as 55 shown. It is to be understood however that the handle may be of any suitable shape or form.

The sheet 2, as best shown in Figure 2, is curved to fit over the eyeball, and the upper 60 edge 4 of the sheet, as best shown in Figure 1, is curved inwardly to register with the edge of the eyelid when closed. The curvature of the sheet and the upper curved edge thereof readily adapts the guard for placement between the eyelid and eyelashes to support the lashes and to protect the lid when the lashes are being painted. The particular construction of the guard, namely the formation of the outwardly projecting wing portions 6, together with the flexibility of the material used in the sheet 2, gives a certain degree of flex 65 to the guard and permits it to conform to a certain extent with the shape of a particular 70 person's eye.

In use, as illustrated in Figure 3, the handle 3 of the guard is grasped by the hand and the guard sheet 2 placed over the lower eyelid with the upper curved edge 4 positioned at the base of the eyelashes. By now closing 80 the eye the eyelashes of the upper lid are brought down and together with the lashes of the lower lid lie on the upper surface of the guard sheet 2. This provides a support for 85 painting or otherwise applying the coloring matter to the lashes, and at the same time protects the lower lid from being smeared by the paint. Of course the device may be used on each eyelid separately if desired.

I claim:

1. An eyelid guard comprising a sheet adapted for placement between the lower eyelid and the eyelashes to support the lashes and to protect the lid when the lashes are being colored, the upper edge of said sheet terminating at the base of the lashes.

2. An eyelid guard comprising a handle, and a sheet secured to the handle and adapted for placement between the lower eyelid and the eyelashes to support the lashes and to pro-

tect the lid when the lashes are being colored, the upper edge of said sheet terminating at the base of the lashes.

3. An eyelid guard comprising a flexible sheet adapted for placement between the lower eyelid and the eyelashes to support the lashes and to protect the lid when the lashes are being colored, the upper edge of said sheet terminating at the base of the lashes.

10 4. An eyelid guard comprising a sheet curved to fit over the eyeball and having the upper edge thereof curved to register with the edge of the eyelid when closed, said sheet being adapted for placement between the lower eyelid and the eyelashes to support the lashes and to protect the lid when the lashes are being colored, said sheet covering the lower eyelid only so that the upper lid is free to move.

15 5. An eyelid guard comprising a sheet adapted for placement over the lower eyelid only so that the upper lid is free to move, and upon which the lashes of both lids are adapted to lie when the eye is closed so that the sheet provides a support for the lashes and protection for the lid when the lashes are being colored.

In testimony whereof I have hereunto set my hand.
